UNITED STATES PATENT OFFICE

165,591

HYPODERMIC NEEDLE

James W. Lee, Westfield, N. J., assignor to Cook-Waite Laboratories, Inc., New York, N. Y., a corporation of Delaware

Application July 18, 1951, Serial No. 15,931

Term of patent 14 years

(Cl. D83—1)

To all whom it may concern:

Be it known that I, James W. Lee, a citizen of the United States, residing at Westfield, in the county of Union, State of New Jersey, have invented a new, original, and ornamental Design for a Hypodermic Needle, of which the following is a specification, reference being had to the accompanying drawing, forming a part hereof.

Fig. 1 is a perspective view of a hypodermic needle embodying my new design.

Fig. 2 is a plan view of the needle.

Fig. 3 is a side view of the needle.

I claim:
The ornamental design for a hypodermic needle, as shown.

JAMES W. LEE.
